(57) **CLAIM**

The ornamental design for a pet carrier, as shown and described.

DESCRIPTION

FIG. 1 is a front-left perspective view of a pet carrier.

FIG. 2 is a back-left perspective view of the pet carrier.

FIG. 3 is a left elevation view of the pet carrier.

FIG. 4 is a back elevation view of the pet carrier.

FIG. 5 is a front elevation view of the pet carrier.

FIG. 6 is a right elevation view of the pet carrier.

FIG. 7 is a top elevation view of the pet carrier.

FIG. 8 is a bottom elevation view of the pet carrier; and, FIG. 9 is a perspective view of the pet carrier, when used with a luggage, wherein the luggage is shown for illustrative purpose.

The broken lines showing of belts, handles, holes, button nails, stitching lines and an attached luggage are for the purpose of illustrating the overall design of the pet carrier and form no part of the claimed design.
